FIRE EXTINGUISHER HANGER

Barney Schmansky, Pontiac, Mich.

Application February 16, 1933. Serial No. 657,141

4 Claims. (Cl. 248—20)

My present application is filed in the place and stead of my abandoned application filed Nov. 22, 1929, Serial No. 409,029.

This invention relates to a contrivance which may be conveniently referred to as a hanger, the same being expressly constructed for supporting a chemical fire extinguisher of the type used in public buildings, offices, homes, and elsewhere. As a general rule, the chemical fire extinguisher is provided with one or more handle-like bails, one of which is engaged over a suspension or hanger hook on an appropriate supporting surface disposed in readiness for use in case of emergency.

15 The purpose of the present invention is to provide a new type of hanger which is in the nature of a safety appliance permitting the fire extinguisher to be successfully suspended in an inactive state so long as it is in condition for use; that is, filled with the chemicals, but so constructed as to prevent replacement of the extinguisher by untrained hands, or to permit replacement of a used extinguisher.

20 The idea involved in this arrangement is to avoid the hanging on the hook, of an extinguisher which was previously used and which is not in condition for reuse so as to avoid a catastrophe, and to make it necessary to replace the used extinguisher with one which is in condition for action in case of a subsequent emergency or fire.

25 Briefly, this idea is involved in a structure including a key-controlled device which is automatic in the sense that as soon as the fire extinguisher is removed from the hanger, the latter will become ineffective through the automatic action of a retracting and retaining lock. Thus, in order to render the hanger again available, it is necessary to unlock it, this being done by an authorized person, so that it will be in proper condition for re-use when another emergency arises.

30 The particular structure for accomplishing these results will become more readily apparent from the following description and drawings.

In the drawings:—

35 Figure 1 is a front elevational view of a hanger constructed in accordance with the present invention.

40 Figure 2 is a top plan view thereof.

45 Figure 3 is a central vertical sectional view through the structure showing the cover plate covering the suspension hook, rendering the hanger out of use until the lock is opened by a

key in the possession of an authorized officer or person.

50 Figure 4 is a view like Figure 3 showing the hooks uncovered with the fire extinguisher in position for ready use.

55 Figure 5 is a rear elevational view with portions broken away to show the internal details.

60 Figure 6 is a side view of the shackle of the lock.

65 Figure 7 is a front view of Figure 6, observing in a direction from left to right.

70 In the drawings, the reference character 8 designates a plate on which a substantially rectangular box-like housing 9 is mounted. This housing is formed in the top with a key entrance hole 10. The front is provided with a slot as at 11 to facilitate entrance of the handle 12 on the fire extinguisher 13 as seen in Figure 4. The side walls of the housing are cut away to form hooks 14 which when uncovered receive the 75 handle 12 as shown in Figure 4.

75 Inside of the housing is a suitable lock casing 15 having a key-hole 16, Figure 2, for reception of an appropriate key 17 as indicated in dotted lines in Figure 1. The lock includes a U-shaped shackle 18 which is provided with a stem 19 as seen in Figure 7, having upper and lower fingers 20 and 20a which function as keepers. These engage over the channel-shaped portion 21 of the cover plate. The cover plate is in the nature 80 of a slide 22 of channel-shaped design mounted for sliding action inside of the housing and it includes a lower portion 23 to serve as a shutter for the slot 11 and the hooks 14 as well as an extension shelf or flange 24.

85 Inside of the casing are lifting coiled springs 85 which serve to lift the shutter to closing position and to cause it to be locked as the shackle 18 moves into the lock casing 15. Thus the shackle 90 is operatively connected with the spring-pressed 95 shutter.

95 So long as the shackle 18 is held down as seen in Figure 4, the slide or shutter plate uncovers the slot 11 and suspension hooks 14. The hanger is thus rendered ready for receiving the suspension element 12 of the extinguisher 13 as shown in Figure 4. This renders the extinguisher ready for removal in case of fire.

100 As soon however, as the extinguisher is lifted out of the slot and removed from the hooks 14, 105 the springs 25 come into play and slide the shutter up to the position shown in Figure 3, thus covering the slot and the hooks for preventing accidental or thoughtless replacement of the used extinguisher. This avoids a catastrophe such as 110

would happen in the event of a second emergency with a defective extinguisher on the hanger.

This makes it compulsory on the part of the user to replace the extinguisher with one which is properly filled or new, and in order to do this, the lock must be unlocked to permit the shutter to move down to the position shown in Figure 4. Thus the device is in effect an efficient reminder and safety appliance.

10 A careful consideration of the description in connection with the drawings will enable the reader to obtain a clear understanding of the construction, arrangements, and features and advantages therefore, a more lengthy description is regarded as unnecessary.

15 Minor changes in shape, size and rearrangement of details coming within the field of invention claimed may be resorted to in actual practice if desired.

20 What is claimed is:—

1. In a hanger of the class described, a hollow box-like housing provided with a handle receiving slot and suspension hooks at the opposite ends of said slot, a spring pressed slide in said housing 25 including a shutter plate adapted to entirely cover said slot and hooks, a lock casing in said housing including a shackle having operating connection with said slide.

2. In a hanger and in combination, a housing 30 having a slot in one of its walls and also having

hook means in communication with said slot and closed when the slot is closed, a spring influenced shutter arranged in one position to close said slot, and lock-controlled means for preventing movement of the shutter from said position save when the lock is actuated by its complementary key. 80

3. In a hanger and in combination, a housing having a slot in one of its walls and also having hook means in communication with said slot and closed when the slot is closed, a spring influenced shutter arranged in one position to close said slot, and lock-controlled means for preventing movement of the shutter from said position save when the lock is actuated by its complementary key; said shutter having a projection extending 90 through and movable in said slot.

4. In a hanger and in combination, a housing having a slot in one of its walls and also having hook means in communication with said slot, a spring influenced shutter movable in the housing 95 and having a U-shaped inwardly extending portion and also having a projection extending through and movable in the slot, said shutter adapted in one position to close said slot, and lock-controlled means engaging said U-shaped portion for preventing movement of the shutter from 100 said position save when the lock is actuated by its complementary key.
